CLAIM

The ornamental design for an electric connector, as shown and described.

DESCRIPTION

FIG. 1 is front view of an electric connector showing my new design;

FIG. 2 is a left side view thereof;

FIG. 3 is a right side view thereof;

FIG. 4 is a top plan view thereof;

FIG. 5 is a bottom view thereof;

FIG. 6 is a front, left side, top perspective view thereof;

FIG. 7 is a rear, right side, bottom perspective view thereof;

FIG. 8 is a left perspective view of the left side view thereof; and,

FIG. 9 is a right perspective view of the left side view thereof.

A rear view is omitted because the rear view is symmetrical to the front view. The broken lines in the drawings illustrate portions of the electric connector that form no part of the claimed design.
